MOUNTING PAD FOR TRANSISTOR UNIT AND THE LIKE

Nathaniel R. Vincent, Santa Monica, Calif., assignor to
Douglas Aircraft Company, Inc., Santa Monica, Calif.

Filed Dec. 26, 1962, Ser. No. 72,952

Term of patent 14 years

(Cl. D26—10)

FIGURE 1 is a perspective view taken from the front of a mounting pad for transistor unit and the like embodying my new design;

FIGURE 2 is a top plan view thereof;

FIGURE 3 is a side elevational view including a fragmentary sectional view through one of the tapered passageways thereof, as taken along the line 3—3 indicated in FIGURE 2; and

FIGURE 4 is a bottom plan view thereof.

I claim:

The ornamental design for a mounting pad for transistor unit and the like, substantially as shown.
